E. A. ROSENBERG,
WINDOW LOCKING DEVICE,
APPLICATION FILED JUNE 24, 1920.

1,389,072.

Patented Aug. 30, 1921.

UNITED STATES PATENT OFFICE.

EPHEEM A. ROSENBERG, OF DETROIT, MICHIGAN.

WINDOW-LOCKING DEVICE.

1,389,072.

Specification of Letters Patent. Patented Aug. 30, 1921.

Application filed June 24, 1920. Serial No. 391,267.

To all whom it may concern:

Be it known that I, EPHEEM A. ROSENBERG, a citizen of Russia, residing at Detroit, in the county of Wayne and State of Michigan, have invented certain new and useful Improvements in Window-Locking Devices, of which the following is a specification, reference being had therein to the accompanying drawings.

10 This invention relates to a window locking device, and has special reference to that class of devices carried by window sashes for connecting the sashes together so that the sashes may be adjusted in synchronism.

15 My invention aims to provide simple and durable pieces of hardware that may be easily and quickly attached to window sashes to permit of a lower sash being automatically connected to an upper sash, when the

20 lower sash is raised or opened, thus preventing excessive adjustment of the lower sash and any adjustment without moving the upper sash. The advantage gained by such a constructive arrangement of parts is that of

25 limiting the opening movement of the lower sash relative to an upper sash and permitting of the operator of the lower sash adjusting the upper sash without using a sash stick or similar tool. Then again, proper

30 ventilation of an apartment is had when a lower sash is closed, by reason of the upper sash being opened due to its connection with the lower sash. This connection, however, is optional and provision is also made to

35 compensate for sashes of different thicknesses, thus permitting of the locking device being applied to any window sashes to prevent burglarizing.

The mechanical construction entering into my invention will be hereinafter more fully described, and then claimed, and reference will now be had to the drawings, wherein—

40 Figure 1 is a perspective view of a portion of a window frame and sashes, showing the sashes articulated for movement in synchronism;

45 Fig. 2 is a vertical sectional view of a portion of the sashes in closed positions, showing the device to be automatically actuated by the lower sash, and

50 Fig. 3 is an enlarged detail sectional view of the locking devices articulating the window sashes.

In the drawing, the reference numeral 1 denotes the meeting rail of a lower window sash 2 and 3 is one of the side rails of an up-

per sash 4, these window sashes being adjustable in a conventional form of window frame 5.

60 6 denotes a channel ratchet member vertically disposed on the side rail 3 of the upper sash 4, and connected thereto by screws 7 or other fastening means, said channel ratchet member being positioned at a desired height above the meeting rail 8 of the upper sash. 65

The channel ratchet member 6 has its side walls 9 provided with a series of notches 10 and the lower ends of the side walls 9 terminate in stop members 11, which project outwardly from the member 6 and provide a 70 central guide slot 12. Pivots mounted in the inner end of the slot 12 is the slotted end of an arm 13, the slotted end of said arm receiving a transverse pin 14 of the member 6. The outer end of the arm 13 has 75 a series of apertures 15 and pivotally connected to said arm by a transverse pin 16 extending through one of the apertures is a hook shaped latch 17 having a transverse finger piece 18 which also serves as a weight. 80

The pin 16 besides pivotally connecting the latch 17 to the arm 13 serves as a support in the side walls 9 of the member 6 for holding the arm 7 in approximately a vertical position with the lower slotted end 85 of said arm protruding from the lower end of the member 6, as best shown in Fig. 2, and when the arm is in such position the latch 17 hangs from the upper end of the arm and partially within the channel member. 90

19 denotes a keeper mounted on the meeting rail 1 of the lower sash 2 at the upper end of the side rail of said sash, and this keeper is adapted to be engaged by the latch 17 when the lower sash is employed for lowering the upper sash, also when the sashes are locked together. 95

The normal condition of the locking device is shown in Fig. 2, and assuming that the lower sash is raised the meeting rail 100 1 thereof impinges against the inner end of the arm 13 and raises said arm so that the ends of the pin 16 will ride out of the notches 10 of the channel member. On account of the pivotal arrangement of the arm 13, the 105 weighted latch 17 causes the arm 13 to swing downwardly in the slot 12 and assume a horizontal position on said meeting rails 1, with the latch 17 extending under the keeper 19. During this operation the upward 110 movement of the lower sash 2 is limited by the channel member 6 and by reason of the

sashes being locked together by the arm 13 and the latch 17 the lower sash cannot be lowered without lowering the upper sash nor can the upper sash be lowered without 5 lowering the lower sash. It is therefore obvious that when an operator closes the lower sash 2 that the upper sash 4 is lowered for ventilating purposes, but should the operator desire to close the sash 2 without opening the sash 4 then the latch 17 is elevated and the arm 13 placed within the channel member 6, as shown in Fig. 2.

10 The pieces of hardware may be finished to harmonize with finish of the sashes 2 and 4, and while in the drawing there is 15 illustrated the preferred embodiment of my invention, it is to be understood that the structural elements are susceptible to such changes, in size, shape and manner of assem- 20 blage as fall within the scope of the appended claims.

What I claim is:

1. The combination of an upper sash, a 25 lower sash, a keeper on the inner face of said lower sash, and an arm carried by a side rail of said upper sash above the meeting rail thereof and adapted to be shifted by the meeting rail of said lower sash en- 30 gaging the lower end of said arm when said lower sash is raised to cause said arm to engage said keeper and connect said sashes so that the upper sash may be lowered with the lower sash.

2. The combination set forth in claim 1,

wherein a channel member supports said 35 arm and is connected to the upper sash to support said arm in a position to be actuated by the meeting rail of said lower sash.

3. A window lock device comprising a channel member adapted for attachment to 40 the side rail of an upper sash to limit the upward movement of a lower sash, an arm loosely connected to said member, a latch carried by said arm, a pin connecting said latch to said arm and adapted to support 45 said arm in said member to be engaged, and shifted by the rail of the lower sash and a keeper adapted for attachment to the lower sash to be engaged by said latch to articulate the sashes so that said sashes may 50 be lowered in synchronism.

4. A window locking device as characterized in claim 3, wherein the channel member is notched to receive said pin, and said pin adjustable relative to said arm to compensate for sashes of different thicknesses. 55

5. The combination of an upper sash, a lower sash, and means carried by said upper sash normally supported to be actuated by the raising said lower sash to articulate 60 said sashes so that said sashes may be lowered together.

In testimony whereof I affix my signature in the presence of two witnesses.

EPHEEM A. ROSENBERG.
